Specification for Design.

Patented Nov. 9, 1920.

Application filed February 12, 1920. Serial No. 358,157. Term of patent 7 years.

To all whom it may concern:

Be it known that I, WENTWORTH E. OSBORN, a citizen of the United States of America, and a resident of Glen Morris, county of Queens, and State of New York, have invented a new, original, and ornamental Design for Watch-Charms, of which the following description, in connection with the accompanying drawing, is a specification.

In the drawings, Figure 1 represents a

view in elevation of one face of the watch charm, Fig. 2 a view in elevation of the other face, and Fig. 3 a view in elevation looking toward one edge of the watch charm.

I claim as my invention:

The ornamental design for a watch charm as shown.

WENTWORTH E. OSBORN.
